UNITED STATES PATENT OFFICE.

FRANK YOUNG, OF KNIGHT'S LANDING, CALIFORNIA.

DESIGN FOR A CUFF.

SPECIFICATION forming part of Design No. 27,027, dated May 4, 1897.

Application filed March 22, 1897. Serial No. 628,787. Term of patent 7 years.

To all whom it may concern:

Be it known that I, FRANK YOUNG, a citizen of the United States, residing at Knight's Landing, in the county of Yolo and State of California, have invented and produced a certain new and original Design for Cuffs; and I do declare the following to be a full, clear, and exact description of the invention, such as will enable others skilled in the art to which it appertains to make and use the same.

My invention relates to a new and original design for a cuff; and it consists of a cuff of the configuration and outline shown in the accompanying drawings, in which—

Figure 1 is a plan view of the cuff-blank, and Fig. 2 is a view of a cuff when folded in position for use.

The leading features of my design are set forth in the following description:

The cuff consists of a rectangular body, the upper corners of which are cut away, as shown at A, and are creased, as shown at B, to form the triangular flaps C. The base of one of the cut-away corners is straight, as shown at D, while the base of the other corner is rounded, as shown at E. Immediately below these bases are formed slits G.

Having thus described my design, what I claim, and desire to secure by Letters Patent of the United States, is—

The design for a cuff, substantially as herein described and shown.

In testimony whereof I hereunto affix my signature in presence of two witnesses.

FRANK YOUNG.
